CHARGE FORMING DEVICE

Application filed June 27, 1929. Serial No. 374,118.

This invention relates to charge forming devices for internal combustion engines, and more particularly to devices of this character which comprise a plurality of primary carburetors, which deliver a primary mixture of fuel and air to a plurality of secondary mixing chambers located adjacent the engine intake ports and in which the primary mixture is mixed with additional air under certain operating conditions. Devices of this character are disclosed in the copending application of Fred E. Aseltine and Wilford H. Teeter, Serial No. 221,371, filed September 22, 1927.

It is the principal object of the present invention to provide a device of this character in which a minimum amount of fuel is consumed without reducing the engine efficiency. More particularly, it is the object of this invention to provide means for proportioning the mixture which is effective to supply a relatively lean mixture during operation throughout the normal driving range and a somewhat richer mixture when operating with the throttle nearly closed or substantially wide open.

This invention is in the nature of an improvement on the later application above referred to and comprises an auxiliary air inlet adapted to admit additional air to the air passage which supplies air to the secondary mixing chambers. This passage is normally closed by means of a valve which is operated by the primary throttle and is adapted to be opened when said throttle occupies an intermediate position, but is adapted to be closed when the throttle is substantially in closed position, or in substantially fully open position. A suction operated valve is also provided in said auxiliary air passage to regulate the air flowing therethrough in accordance with the manifold vacuum, so as to variably control the proportions of the mixture as the engine suction varies.

Further objects and advantages of the present invention will be apparent from the following description, reference being had to the accompanying drawings wherein a preferred embodiment of one form of the present invention is clearly shown.

In the drawings:

Fig. 1 is a vertical, longitudinal section through a charge forming device constructed in accordance with the present invention and the intake port with which it is associated. 55

Fig. 2 is a fragmentary, transverse, vertical section on the line 2—2 of Fig. 1.

Fig. 3 is a fragmentary section on the line 3—3 of Fig. 1.

The device disclosed comprises a main air manifold 10, having three outlet branches, the middle branch 12 being shown herein. Each of these branches communicates with one of the intake ports 14 of a multicylinder engine. The outlet branches are each provided with an attaching flange 16 for securing the manifold to the engine block in the usual manner, and a flange 18 to which the carburetor unit is secured. 60 65

The carburetor unit comprises a main housing 20, having an attaching flange 22, adapted to be secured to the flange 18 by screws 24. An air inlet coupling 28 is secured in position to register with an opening in the upper wall of the housing 20, in any suitable 70 75 way and may be connected with an air cleaner if desired. A casting 30, in which the passages supplying fuel to the nozzles are formed, is secured by screws to the lower wall of housing 20, and a sheet metal fuel bowl 32 is held 80 tight against an annular shoulder 34 on the housing by any suitable means. Fuel is conducted from a main source of supply to the fuel bowl through a conduit (not shown) and the flow of fuel to the bowl is controlled by 85 a float 36, operating in the usual manner to maintain a substantially constant level of fuel therein.

Fuel flows from the bowl 32 to a plurality of primary fuel nozzles 38, one of which is 90 located in each of the primary mixing chambers 40, the construction of which is briefly described hereinafter. The fuel conduit between the fuel bowl and the nozzles comprises the vertical fuel passage 42 communicating 95 at its upper end with the horizontal fuel canal 44, which connects with each of the nozzles 38 through an orifice 46. Fuel is admitted from the fuel bowl to the passage 42 at all engine speeds, through a fixed metering orifice 48 100

and at high speeds additional fuel is admitted through an orifice 50 controlled by a valve 52, operated in the manner set forth in the above mentioned application. This operating means forms no part of the present invention and need not be described further herein.

Fuel is lifted from the fuel bowl through the above described fuel passages and nozzles 38 to the primary mixing chambers by the suction therein. Opening movements of the 10 throttle cause a reduction in mixing chamber suction which might permit the fuel column to drop sufficiently to cause a temporary fuel starving of the engine unless means are provided to prevent this action. For this purpose a check valve 54 is provided in an enlarged chamber 56 at the junction of the channels 42 and 44, and on reduction of mixing chamber suction, seats on the bottom of 15 the chamber, preventing downward flow of fuel.

Each primary fuel nozzle is provided with a main fuel outlet 58 in the top of the nozzle and a secondary fuel outlet comprising two 20 orifices 60 and 62 in the vertical wall of the nozzle near the bottom of the mixing chamber. At relatively high speeds, the mixing chamber suction is sufficient to lift fuel from the main outlet as well as from orifices 60 25 and 62. At idling, or low speed operation under load, however, the suction is enough to lift fuel only to some point between the top of the nozzle and the orifices 60 and 62, fuel flowing from these orifices by the action 30 of gravity under such operating conditions. Each nozzle is provided with a restricted fuel metering orifice 63. The primary mixing chambers comprise the enlarged anterior ends of the primary mixture passages 64, 35 which are parallel to each other and close together, as indicated in Fig. 2. When the carburetor is attached to the manifold, these passages register with conduits which convey the primary mixture to the secondary 40 mixing chambers, as fully disclosed in the application above referred to. Restrictions 45 separate the primary mixing chambers from the remainder of the mixture passages to reduce the velocity of flow past the fuel 50 nozzles for a purpose fully set forth in the above mentioned copending application.

A single throttle valve 68, which extends across all the primary mixture passages, controls the flow therethrough and is provided 55 with grooves 70, which register with said mixture passages. This throttle is operated by means hereinafter more fully described. The middle primary mixture passage communicates with a tube 72 fixed in the manifold branch 12. This tube constitutes one of the primary mixture conduits above referred to and conveys the primary mixture to the secondary mixing chamber located in the middle branch of the manifold.

65 Nearly all of the air entering the carbure-

tor flows through the inlet coupling 28 and is controlled by the main air valve 74, normally held against a seat 76 by a spring 78, received between the valve and a flange 80, projecting from a sleeve 82, slidably mounted on a stationary guide sleeve 84, fixed in the housing 20, and serving also as a guide for the stem 86 to which the air valve is secured. When it is desired to choke the carburetor to facilitate starting of the engine, the flange 75 80 is adapted to be lifted by means not shown herein, but fully described in the above application, until the upper end of the sleeve 82 engages the air valve to hold it closed. Sufficient air to carry the starting fuel from the nozzles to the intake ports is admitted through an elongated slot 90, formed in a plate 92, secured to the housing 20, as shown in Fig. 1.

The valve 74 admits air to the air chamber 94 from which air flows to the primary mixture passage, through an orifice 96 in the bottom of the air chamber and to the secondary mixing chambers through a passage 98, which connects with the inlet of the manifold 10. A manually operable throttle 100 secured to a shaft 102, rotatably mounted in the housing and operated by means hereinafter fully described, controls the flow of air through 95 the passage 98.

The operating connections for the two throttle valves constitute no part of the present invention and are not disclosed herein, it being sufficient for the purpose of this disclosure to describe briefly the mode of operation of these valves. The primary throttle 68 is connected to the main air throttle 100 by a lost motion connection which permits a predetermined movement of the primary throttle independent of the throttle 100 and is capable of adjustment. It is generally adjusted so that the primary throttle is moved without accompanying movement of the air throttle until the former reaches a position corresponding to a vehicular speed of approximately 15-20 miles per hour on the level. On further opening of the primary throttle the air throttle is moved simultaneously therewith.

On opening of one or both of the throttle valves the suction in the air chamber 94 is increased and the valve 74 is opened to admit additional air and increase the quantity of mixture supplied to the engine. The opening of this valve must be retarded to prevent fluttering of the valve and to prevent admission of enough air to dilute the mixture. For this purpose a dashpot is provided comprising a cylinder 104 formed in the casting 30 and a piston 106 secured to the lower end of 120 the valve stem 86 by any suitable means. This dashpot is of conventional form and its specific construction is not material to the present invention.

125 In order to accomplish the object of this 130

invention the main housing 20 is cast with an external flat surface 108 as shown in Fig. 3. Secured to this flat surface by screws 110 is a small casting 112 having a passage 5 114 formed therein for supplying additional air to the secondary air passage. A bore 116 in the casting 112 communicates with a larger orifice 118 in the wall of the main housing immediately in front of the air throttle 100 to 10 permit the flow of air from the passage 114 into the secondary air passage as described. The passage 114 is normally closed by a plate 120 pivoted on a pin 122 secured in any suitable manner in the casting 112. The plate is 15 provided with a slot 124 which is moved into registry with the passage 114 when the primary throttle is moved to intermediate positions, but is moved out of registry with said passage 114 before the throttle reaches its 20 fully opened position.

In order to move the plate 120 in the manner described an operating arm 126 is secured to a hub 128 pinned to the spindle 130 projecting from the primary throttle, so as to 25 rotate therewith. The arm 126 has a slot 132 in its free end which engages a pin 134 projecting laterally from the lower end of the plate 120 so as to rock the plate on its pivot when the arm is moved with the 30 throttle. On counterclockwise or opening movement of the throttle the plate 120 will be rotated in a clockwise direction from the position shown in Fig. 1 to move the slot 124 into engagement with passage 114 and continued 35 opening movement of the throttle will move said slot beyond the passage 114 to again close said passage as the primary throttle reaches its fully opened position. A spring 136 surrounds the pin 122 between the 40 plate 120 and a collar 138 on the pin 122 so as to press the plate 120 into engagement with the casting 112, preventing material leakage of air into the passage 114 when the plate 120 is in position to close said passage.

As described above the plate 120 opens and closes the passage 114 but the flow of air through said passage when the latter is open is controlled by a suction operated valve 140 which is positioned within the orifice 118 and is of somewhat larger size than the bore 50 116 so that the valve closes this bore when in its closed position as shown in Fig. 3. The valve is secured to the end of a valve stem 142 slideable in a bore in the casting 112 and normally held in closed position by a spring 144 surrounding the valve stem and received between the casting 112 and an enlarged head 146 on the valve. Obviously, the position 55 of this valve will vary in accordance with variations in the suction between the air throttle 100 and the intake port and will variably control the richness of the mixture in accordance with such suction.

The secondary mixing chambers comprise 60 venturi tubes 150 which are positioned in the

outlet branches of the manifold adjacent the outlet ends of the primary mixture conduits. These venturi tubes are identical and each is provided with an external rib 152 adapted to be clamped between shoulders 154 and 156 70 on the manifold and the engine block respectively when the device is assembled. These tubes accelerate the flow of air past the delivery ends of the primary mixture conduits, increasing the velocity of flow therethrough 75 as fully set forth in the earlier of the above mentioned applications.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a secondary mixing chamber, a primary mixture passage delivering a primary mixture of fuel and air thereto, means for supplying fuel and air to said mixture passage, a primary throttle regulating the flow therethrough, a secondary air passage supplying air to said secondary mixing chamber, means for regulating the mixture proportions comprising an auxiliary air passage communicating directly with the atmosphere and supplying air to the secondary air passage and means operated by the primary throttle for controlling the flow of air through said passage.

2. A charge forming device for internal combustion engines comprising a secondary mixing chamber, a primary mixture passage delivering a primary mixture of fuel and air thereto, means for supplying fuel and air to said mixture passage, a primary throttle regulating the flow therethrough, a secondary air passage supplying air to the secondary mixing chamber means for regulating the mixture proportions comprising an auxiliary air passage communicating directly with the atmosphere and supplying air to the secondary air passage and means operated by the primary throttle for regulating the flow of air through said passage which is effective to permit a flow therethrough only when the throttle is partially opened.

3. A charge forming device for internal combustion engines comprising a secondary mixing chamber, a primary mixture passage delivering a primary mixture of fuel and air thereto, means for supplying fuel and air to said mixture passage, a primary throttle regulating the flow therethrough, a secondary air passage for supplying air to the secondary mixing chamber, means for regulating the mixture proportions comprising an auxiliary air passage communicating directly with the atmosphere and supplying air to the secondary air passage, a valve controlling the flow through said passage and normally in closed position, means operated by the throttle dur-

ing its opening movement to open said valve and effective after a predetermined movement of the throttle to close said valve.

4. A charge forming device for internal combustion engines comprising a mixture passage, means for supplying fuel and air thereto, a throttle regulating the flow through said passage, a secondary air passage supplying additional air to the mixture passage

10 means for regulating the proportions of fuel and air in the mixture comprising an auxiliary passage communicating with the atmosphere and supplying air to the secondary air passage, and a plurality of means for controlling the flow through said auxiliary passage.

5. A charge forming device for internal combustion engines comprising a mixture passage, means for supplying fuel and air thereto, a throttle regulating the flow through said passage, a secondary air passage supplying additional air to the mixture passage means for regulating the proportions of fuel and air in the mixture comprising an auxiliary passage communicating with the atmosphere and supplying air to the secondary air passage, means operated by the throttle for rendering said auxiliary passage effective and means operated by the suction of the engine for controlling the flow through said passage.

6. A charge forming device for internal combustion engines comprising a plurality of secondary mixing chambers, a plurality of primary mixture passages for supplying a primary mixture of fuel and air thereto, a primary throttle valve controlling the flow through all of the primary mixture passages, means for regulating the proportions of fuel and air in the mixture comprising an auxiliary air passage adapted to supply air to the mixture formed in all of said primary mixture passages and means operated by the primary throttle for controlling the flow through said passage.

7. A charge forming device for internal combustion engines comprising a plurality of secondary mixing chambers, a plurality of primary mixture passages for supplying a primary mixture of fuel and air thereto, a primary throttle valve controlling the flow through all of the primary mixture passages, means for regulating the proportions of fuel and air in the mixture comprising an auxiliary air passage adapted to supply air to the mixture formed in all of said primary mixture passages, and a plurality of means for controlling the flow through said passage, one of said means being operated by the manifold vacuum and the other by the primary throttle.

8. A charge forming device for internal combustion engines comprising a plurality of secondary mixing chambers, a plurality of primary mixture passages for supplying a primary mixture of fuel and air thereto,

primary throttle valve controlling the flow through all of the primary mixture passages, a secondary air passage supplying air to all of said secondary mixing chambers, and means for regulating the mixture proportions comprising an auxiliary air passage communicating with the atmosphere and adapted to admit air to the secondary air passage under certain operating conditions.

9. A charge forming device for internal combustion engines comprising a plurality of secondary mixing chambers, a plurality of primary mixture passages for supplying a primary mixture of fuel and air thereto, a primary throttle valve controlling the flow through all of the primary mixture passages, a secondary air passage supplying air to all of said secondary mixing chambers, an air throttle in said passage, means for regulating the mixture proportions comprising an auxiliary air passage admitting air to said secondary air passage posterior to the throttle therein.

10. A charge forming device for internal combustion engines comprising a plurality of secondary mixing chambers, a plurality of primary mixture passages for supplying a primary mixture of fuel and air thereto, a primary throttle valve controlling the flow through all of the primary mixture passages, a secondary air passage supplying air to all of said secondary mixing chambers, an air throttle in said passage, means for regulating the mixture proportions comprising an auxiliary air passage admitting air to said secondary air passage posterior to the throttle therein, and means operated by the primary throttle for controlling the flow through said passage.

11. A charge forming device for internal combustion engines comprising a secondary mixing chamber, a primary mixture passage delivering a primary mixture of fuel and air thereto, means for supplying fuel and air to said mixture passage, a primary throttle regulating the flow therethrough, a secondary air passage supplying air to the secondary mixing chamber, means for regulating the mixture proportions comprising an auxiliary air passage admitting air to the secondary air passage, and means for regulating the flow through said passage in accordance with variations in engine suction.

In testimony whereof I hereto affix my signature.

FRED E. ASELTINE. 120
